METHOD OF DECOMPOSING OIL TO OLEFINS

Theodore Nagel, Brooklyn, N. Y.

Application March 9, 1938, Serial No. 194,861

3 Claims. (Cl. 260—683)

This invention is directed to a method of decomposing oil to olefins, namely: aliphatic unsaturated hydrocarbons of the homologous series $C_n H_{2n}$. "Oil" is to be considered as crude petroleum or liquids derived from crude petroleum.

Broadly speaking, my invention provides a thermal process for decomposing hydrocarbons while subjected to several atmospheres pressure and preferably to partial pressure of the hydrocarbons in the order of atmospheric or lower pressure, the pressure serving to overcome the resistance to mass flow through subsequent operations of cooling, fractionating, etc., and consists in controlling the thermal process so as to decompose the hydrocarbons to decomposition products composed of olefins as the major hydrocarbons yield and prevent reactions producing polymer products at the expense of the high yield of olefins.

0 By the method of this invention for producing olefins from oil, a close range decomposition temperature is attained to flash decompose the oil to decomposition hydrocarbons without polymerizing reactions taking place, the decomposition products being shock cooled to below the polymerizing temperature zone to retain the highly reactive olefins as decomposition products and also to prevent further decomposition.

Oil charging stocks heavier than the lower boiling liquid derivatives or fractions of crude petroleum, namely, heavier than the grades classed as light distillates and gas oils may be preheated. Preheating can be effected by direct heat exchange—shock cooling the decomposition products with the heavier oil charging stocks, or when the charging stock is preheated from an external source of heat then the oil charging stock should be rapidly preheated while subjected to superatmospheric pressure, the preheat temperature to be slightly below the vaporizing temperature at the pressure to which the oil is subjected, thereby to maintain the oil as a liquid. Preheating these heavier oil charging stocks serves to prepare the oil for flash decomposition upon continuously dispersing the oil throughout a hot zone.

The oil charging stock is continuously injected into a continuously flowing hot gas which contains sufficient heat for heat exchange to the oil to flash decompose the oil at a close range temperature within a temperature range from 1000° F. to 1600° F. At said close range temperature the hydrocarbons of the oil are decomposed to decomposition hydrocarbons, the major portion of which is olefins. The flowing decomposition

products are continuously shock cooled to below 900° F. to prevent the highly reactive olefins from reacting to polymer products.

The heating of the oil through the polymerizing reactions temperature zone to the desired close range decomposition temperature and the cooling of the decomposition products to below the polymerizing reactions temperature zone are so controlled that only decomposition of the hydrocarbons takes place, therefore reactions, producing polymer products at the expense of a high yield of olefins, do not occur.

The said desired close range temperature to be attained by flash heating the oil to within a temperature range of from 1000° F. to 1600° F. depends upon the specific olefin, of the open chain homologous series ($C_n H_{2n}$), desired as the major yield decomposition hydrocarbon, so that the higher the said close range temperature attained, within the temperature range from 1000° F. to 1600° F., the lighter weight will be the specific olefin produced as the major yield decomposition hydrocarbon.

For example, where the charging stock is a straight run natural fuel oil of 20° A. P. I., and where the major yield decomposition hydrocarbon desired is ethylene, the temperature to be attained to flash decompose the oil ranges from 1400° F. to 1600° F. At the higher temperatures, from 1500° F., the only olefin produced as the major yield decomposition hydrocarbon will be ethylene—the lightest weight olefin—while at the lower temperatures within the temperature range from 1400° F. to 1600° F. propylene will be minor yield olefin products.

Should the olefin desired as the major yield decomposition product be propylene, then the temperature to be attained to flash decompose the oil is in the order of say 1350° F. to 1400° F.—a narrower temperature range than when ethylene is to be the major yield decomposition product.

As the desired major yield olefin gradually becomes heavier, namely, butylene, amylene, hexylene, etc., the temperature to be attained to flash decompose the oil to the desired olefin becomes lower and the range narrows, until when heptylene, for example, is the desired major yield decomposition hydrocarbon, the temperature to be attained to flash decompose the oil will be in the order of 1150° F., near the low end of the said temperature range from 1000° F. to 1600° F.

In the practice of my improved method, and when operating at the higher temperatures with-

in the said temperature range of 1000° F. to 1600° F. the decomposition hydrocarbon products will be fixed gases, but as the selective close range temperature is gradually lowered liquid decomposition hydrocarbon products appear and gradually increase in quantity with a gradual decrease in the yield of fixed gas, until, when operating at the lower temperature and within the said temperature range the decomposition hydrocarbon products reduced to atmospheric temperature will be mostly liquids and predominantly olefins.

When using 20° A. P. I. oil as the charging stock, the oil may be preheated either by heat exchange shock-cooling the decomposition products or from an external source of heat. In the latter case the oil is subjected to superatmospheric pressure while being rapidly preheated to a temperature slightly below its vaporizing temperature at the pressure employed. The specific oil mentioned, for example, may be heated to a temperature not to exceed 900° F. in a pipe still oil heater at a pressure not less than 150 pounds per square inch. The continuous flow of hot gas used as a heat carrying medium, and heretofore referred to, into which the oil is continuously dispersed, can be generated by combustion of oil or other source of combustion or can be generated within the oil decomposing chamber and consists principally of carbon monoxide and nitrogen produced by continuous partial oxidation of free carbon and the higher boiling end portion of the oil charging stock with a controlled continuous supply of air to produce the reaction temperature and volume of flowing gas required for heat exchange to flash decompose the oil, which is continuously injected into and dispersed throughout the continuously generated and continuously flowing heat-carrying gas, to the said selective close range temperature.

The drawing illustrates merely diagrammatically an apparatus which may be employed in practicing my invention.

Referring to the accompanying drawing and assuming that ethylene is the major yield decomposition hydrocarbon desired: Straight run natural fuel oil, for example, of 20° Baumé gravity, is taken from a suitable source of supply 1 and continuously flows, at a pressure of not less than 150 pounds per square inch, through a pressure pipe still oil heater 2. The liquid oil is rapidly preheated in the still to slightly below its vaporizing temperature, which at the pressure mentioned is in the order of 850° F. The preheated liquid oil is continuously dispersed into a hot zone or oil decomposing chamber and hot gas generator 3, the oil, in the apparatus illustrated, being sprayed or atomized vertically downward in the form of a hollow cone, encountering increasing heat intensity as it flows countercurrent to a continuously upwardly flowing heat-carrying gas with which the oil intermixes within the oil decomposing chamber and hot gas generator 3, the oil being flash decomposed by the heat-carrying gas. The heat-carrying gas referred to is continuously generated in the lower part of the heat insulated chamber 3 by partial oxidation of the free carbon and the higher boiling end portion of the oil charging stock with a controlled continuous flow of air which enters near the base of the chamber 3, as shown at 4. The volume of the heat-carrying gas produced is so controlled that as it flows upward the descending oil is heated to a close range temperature in the order of 1500° F. and flash-decomposed to decomposition products, the

major hydrocarbons yield of which is ethylene, as the flowing mixture is deflected and reaches the outlet 5 of the chamber 3. The continuously flowing decomposition products at outlet 5 are continuously shock cooled below polymerizing temperature by a cooling medium such as oil, steam, water, gas, etc. For example, oil may be continuously sprayed into and shock-cool the products of decomposition as shown at 6, to a temperature in the order of 600° F. to prevent the ethylene reacting to polymer products at the expense of the high yield of ethylene. The cooled decomposition products are continuously discharged through the outlet pipe 7.

It will be seen from all of the foregoing that I have provided for the selective production of olefins from oil, wherein decomposition of the oil to produce a desired olefin as the major yield decomposition product is effected by dispersing the oil continuously into the hot gas resulting from continuous combustion of oil, whereby the oil injected into the resulting combustion product is flash-decomposed, the continuously flowing decomposition products being continuously shock-cooled to below polymerizing temperature.

The above operating example of this process for carrying out the method of producing olefins from oil and the diagrammatic flow sheet serve merely as an illustration of the practice of this invention and may vary so long as the fundamental principles herein described are adhered to.

What I claim is:

1. The method of selectively producing specific olefins of the aliphatic hydrocarbon series C_nH_{2n} as the major hydrocarbon yield resulting from decomposing oil, which method comprises continuously atomizing oil in a zone while introducing air into the zone peripherally thereof and adjacent the base of the zone, continuously generating a hot gas in the zone by partial oxidation of the higher boiling end portion and free carbon of the charging stock with said air, the atomized oil being dispersed into said hot gas, and generation of said hot gas being so controlled that the oil is flash decomposed within the temperature range from 1000° F. to 1600° F. to decomposition hydrocarbons, the major hydrocarbon of which is a desired specific olefin and continuously shock-cooling the flowing decomposition products to below 900° F. to prevent the said specific olefin from reacting to polymer products.

2. The method of producing olefins as the major hydrocarbons yield resulting from decomposing oil, which method comprises continuously atomizing oil in a zone while introducing air into the zone peripherally thereof and adjacent the base of the zone, continuously generating a hot gas in the zone by partial oxidation of the higher boiling end portion and free carbon of the charging stock with said air, the atomized oil moving countercurrent to and being dispersed into said hot gas, and generation of said hot gas being so controlled that the oil is flash decomposed within the temperature range from 1000° F. to 1600° F. to decomposition hydrocarbons, the major portion of which is olefins, and continuously shock-cooling the flowing decomposition products to below polymerizing reactions temperature to retain the olefins.

3. The method of producing olefins as the major hydrocarbons yield resulting from decomposing oil, which method comprises continuously atomizing oil downwardly in a zone while introducing air into the zone peripherally thereof and adjacent the base of the zone, continuously gen-

erating a hot gas in the zone by partial oxidation of the higher boiling end portion and free carbon of the charging stock with said air, the gas moving upwardly and the atomized oil being dispersed thereinto, generation of said gas being so controlled that the oil is flash decomposed within the temperature range from 1000° F. to 1600° F.

to decomposition hydrocarbons, the major portion of which is olefins, and continuously shock-cooling the flowing decomposition products to below polymerizing reactions temperature to retain the olefins.

THEODORE NAGEL.
